his Atty.

UNITED STATES PATENT OFFICE

AUGUSTUS C. DURDIN, JR., OF CHICAGO, ILLINOIS, ASSIGNOR TO CHICAGO PUMP COMPANY, OF CHICAGO, ILLINOIS, A CORPORATION OF ILLINOIS

PRIMING APPARATUS FOR PUMPS

Application filed May 15, 1930. Serial No. 452,550.

This invention relates to pumps, and more particularly to centrifugal pumps. Considerable difficulty has been encountered with pumps of this type when used to pump liquid from a lower level than that of the pump because of the difficulty in priming the pump at the start of the pumping operation, and also because of the difficulty of keeping the pump free from air during the pumping operation. Many attempts have been made to provide automatic means for priming the pump with more or less success, but the particular objection to such automatic priming devices is that they constantly place a load on the priming apparatus, thereby unnecessarily increasing the power required to operate the pump.

The principal object of the present invention is the provision of novel means for extracting the gas or air from a centrifugal pump at the commencement of its operation and also for removing any gas or air from the pump in case any finds its way thereto during operation. Another object is the provision of novel priming means for freeing the liquid pump of air or other gases during the pumping operation without placing any appreciable burden upon the pump motor when the priming means is running idle.

With these and other objects and advantages in view, this invention consists in a centrifugal pump provided with a gas or air pump having a conduit leading from its intake side to the liquid pump and provided with a chamber in which a partial vacuum is created to prime the liquid pump, whereby liquid flows into the chamber, and, as a result, opens a valve to that part of the conduit which leads from the chamber to the gas or air pump, whereby air at atmospheric pressure is admitted to the gas or air pump, thereby relieving said pump of its work. It further consists in a liquid pump of the rotary type provided with a rotary gas or air pump driven from the same source of power as that which drives the liquid pump, and having a conduit connecting the liquid pump with the intake of the gas or air pump and provided with a chamber and valve mecha-

nism for maintaining a partial vacuum in said chamber and admitting air at atmospheric pressure to the gas or air pump when the liquid pump is primed, whereby at such times the gas or air pump may run idle.

It further consists in the several novel features of construction, arrangement and combination of parts hereinafter fully set forth and claimed.

The invention is clearly illustrated in the drawing accompanying this specification in which the figure is a view partly in side elevation and partly in vertical longitudinal section of a liquid pump equipped with priming apparatus embodying a simple form of the present invention.

Referring to said drawing, which is merely schematic and illustrates one form of the invention, the reference character A designates a centrifugal pump of conventional form having an impeller 1 rotating in a volute 2 and mounted upon a shaft 3 journaled in bearings 4 carried by a base 5. The inlet to the liquid pump is indicated at 6 and is connected to a pipe or conduit 7 which, as shown, leads down from the pump to a source of liquid supply. The shaft 3 is connected to and driven by an electric motor or other power device (not shown), as is customary.

Associated with the pump A is a gas or air pump B of conventional form, and said pump B may comprise a pump of the type employing water for its pumping action, or it may comprise the ordinary rotary type of gas or air pump. The gas or air pump B is mounted upon the pump base 5, and, as shown, its impeller 8 is mounted upon the shaft 3 of the liquid pump, although it is to be observed that it may be mounted upon a separate shaft coupled to the shaft of the liquid pump or separately driven from the shaft 3, or other power shaft. When a gas or air pump of the type employing water for its pumping action is used, the water may be supplied thereto by a pipe 9 from any suitable source, as, for instance, the city water pressure.

The liquid pump A is shown in the form of a double-suction pump, the inlet chambers 10 of which communicate with the intake 6

and are disposed at the sides of the impeller 1. When a gas or air pump B of the type employing water for its pumping action is used, an inlet chamber 11 is provided in the casing of the pump which may communicate with the water supply pipe 9.

Connecting the inlet chamber or chambers 10 and 11 of the pump A and gas or air pump B is a conduit C composed of parts designated by the characters 12, 13 and 14, through which the gas or air pump removes gas and air from the inlet chamber or chambers 10 of the liquid pump by creating a partial vacuum therein. In order to prevent any water from being carried from the liquid pump to the gas or air pump, and in order to minimize the load on the gas and air pump after the liquid pump has been primed, the part of the conduit designated by the character 13 is enlarged to provide a float and vacuum chamber for receiving liquid when the liquid pump is being primed, and said float chamber 13 communicates with the part 14 of the conduit through a port 15 controlled by a check valve 16 which remains open while suction is being applied to the float chamber by the gas or air pump.

An air inlet port 17 is provided in the part 14 of the conduit between the float chamber and gas or air pump, which port 17 is controlled by a valve 18 connected to and operated by a float 19 contained in the float chamber 13. In the form of the invention illustrated, the valve 18 is connected to the float 19 by a stem 20, and at the place where the stem 20 extends through the wall 21 which separates the float chamber from the part 14 of the conduit, I provide a seal or joint, here shown in the form of a sylphon bellows 22 hermetically sealed to the wall 21 and stem 20 to prevent any possibility of leakage at this point.

It is to be observed that so long as the float 19 remains at the lower limit of its movement, the valve 18 closes the air inlet port 17, so that the full effect of the gas or air pump is applied through the conduit C to the liquid pump. When the float is raised to the upper limit of its movement, the air inlet port 17 is opened, whereby outside air is admitted to that portion 14 of the conduit which is between the float chamber and the gas or air pump, whereupon the check valve 16 seats itself and closes the port 15, thereby maintaining a partial vacuum in the float chamber and permitting the gas or air pump to run without causing any appreciable vacuum in the part 14 of the conduit.

Inasmuch as it is unnecessary to furnish the gas or air pump shown with water, except when functioning to create vacuum, it is desirable to shut off the supply of water when it is not functioning in this manner, and means have been provided for accomplishing this automatically. As shown, a

shut-off valve 23 is provided on the water supply pipe 9, and said valve 23 is operatively connected with the float valve mechanism, so that when the float valve is raised, which is the case when the liquid pump is fully primed, the valve 23 will be closed, and when the float is lowered, due to the escape of water from the vacuum chamber, the valve 23 will be opened, thereby admitting water to the gas and air pump, whereby it may again function. As shown, the simple means for connecting the float valve mechanism with the valve 23 comprises a lever 24 fulcrumed upon a bracket 25 and having an arm connected to the upper end of the valve stem 20 and its other arm connected to the valve stem of the shut-off valve 23 by a link 26.

In operation, the pumps A and B and conduit C are usually filled with air at the commencement of the pumping operation. At the start the gas or air pump exhausts the air from the liquid pump and when sufficient vacuum is built up therein, the water rises and fills the intake chambers 10 of the liquid pump and enters the vacuum chamber 13 through the parts 12 of the conduit C. The valve 18 remains closed until the water in the vacuum chamber rises sufficiently to overbalance the weight of the float valve mechanism and the pressure on the exterior of the valve 18, whereupon the float is raised and therewith the valve 18 is lifted, thereby uncovering the air inlet port 17 and admitting air at atmospheric pressure to the part 14 of the conduit. Simultaneously, because of the difference in pressure between the vacuum chamber 13 and part 14 of the conduit, the check valve 16 closes, thereby maintaining the partial vacuum in the vacuum chamber.

The liquid pump having been primed, it continues to function as a liquid pump, and inasmuch as the vacuum in the part 14 of the conduit and in the gas or air pump has been broken, the gas or air pump continues to run idly creating little or no vacuum in the part 14 of the conduit, thereby relieving the motor so that all of the power may be utilized in driving the liquid pump. When the shut-off valve 23 is employed, the supply of water is shut off as soon as the float 19 is raised and, consequently, the impeller of the gas or air pump rotates idly, thereby relieving the motor of any effort to operate the gas or air pump, except that required to rotate the impeller.

In case any gas or air finds its way into the float chamber 13 or the liquid pump A, the water in the float chamber recedes, and when the level of the water lowers sufficiently, the float 19 falls, thereby closing the air inlet port 17 through the valve 18, whereupon the gas or air pump quickly builds up a vacuum in the part 14 of the conduit and in the float chamber and, as a result, the water again rises in the float chamber, raises the float and

opens the air inlet port 17. Outside air being admitted to the part 14 of the conduit, the check valve 16 closes and the gas or air pump is again relieved of its work. The operation thus described is continued so long as the liquid pump is in use.

It is to be observed that little or no vacuum is maintained in the part 14 of the conduit during the operation of the liquid pump

- 10 after it has been primed, except when air leaks into the float chamber or liquid pump, and then the gas or air pump functions for a comparatively short time to restore the vacuum in the float chamber. Power that is ordinarily required to operate gas or air pumps for self-priming rotary liquid pumps is reduced to a minimum and utilized for driving the liquid pump. Moreover, the wear and tear on such gas or air pumps is materially 20 reduced.

Furthermore, when the vacuum is broken in the part of the conduit leading from the float chamber to the gas pump, its effect on the pump is to relieve it of its work of creating a vacuum. For this reason, it is especially advantageous to admit an abundance of air at atmospheric pressure to the suction conduit of the gas pump.

It is to be understood that the term "gas pump" as used in this specification, and in the appended claims, is intended to include vacuum pumps generally and particularly those of the rotary type that employ or do not employ water in their pumping action.

- 35 More or less variation of the exact details of construction is possible without departing from the spirit of this invention. I desire, therefore, not to limit myself to the exact form of the construction shown and described, but intend, in the following claims, to point out all of the invention disclosed herein.

I claim as new, and desire to secure by Letters Patent:

- 45 1. Priming apparatus for rotary liquid pumps comprising in combination a gas pump driven with the liquid pump, a conduit connecting the liquid pump with the intake of the gas pump and including a chamber adapted to receive air and liquid from the liquid pump, there being a port between said chamber and that part of the conduit leading therefrom to the gas pump, controlled by a valve opening outward from the chamber, and there being a valve-controlled relief port 50 opening from that part of the conduit which leads from the chamber to the gas pump, having a valve operating independently of said first mentioned valve for admitting outside air to the gas pump through that part of the conduit which leads from the relief port to the gas pump.

60 2. Priming apparatus for rotary liquid pumps comprising in combination a rotary gas pump of the type employing water for its action, a suction conduit connecting the liquid

pump with the intake of the gas and including a vacuum chamber adapted to receive air and liquid from the liquid pump, there being a port between said vacuum chamber and that part of the conduit leading therefrom to the 70 gas pump controlled by a valve opening outward from the chamber, and there being a valve-controlled relief port opening from that part of the conduit which leads from the chamber to the gas pump, having a valve operating independently of said first mentioned valve for admitting air to the gas pump through that part of the conduit which leads from the relief port to the gas pump.

3. Priming apparatus for rotary liquid 80 pumps comprising in combination a gas pump, a conduit connecting the liquid pump with the intake of the gas pump and having a vacuum chamber adapted to receive air and liquid from the liquid pump, there being a 85 port between said chamber and that part of the conduit leading therefrom to the gas pump controlled by a valve opening outward from the chamber, and there being a valve-controlled relief port opening from that part 90 of the conduit which leads from the chamber to the gas pump, having a valve operating independently of said first mentioned valve for establishing communication between said last mentioned part of the conduit and the 95 outer atmosphere whereby outside air is admitted to the gas pump through said part of the conduit, said means being controlled by the volume of liquid contained in the vacuum chamber.

4. Priming apparatus for rotary liquid 100 pumps comprising in combination a gas pump having a driving connection associated with the liquid pump, a conduit connecting the liquid pump with the intake of the gas pump and having a part adapted to receive liquid from the liquid pump, a check valve opening towards the gas pump for opening and closing the passage through the conduit, and means operating independently of said valve, 105 responsive to variations of the volume of liquid in said conduit for admitting outside air to that part of the conduit between the gas pump and the part of the conduit containing the liquid when the check valve is closed.

5. Priming apparatus for rotary liquid 110 pumps comprising in combination a rotary gas pump of the type employing water for its action and having a driving connection associated with the liquid pump, a suction conduit having an incoming part connected to the liquid pump and an outgoing part connected to the intake of the gas pump, a pressure-operated valve between the two parts of the conduit opening towards the gas pump for controlling the passage through said conduit whereby vacuum is capable of being maintained on the incoming part side of said conduit and atmospheric pressure on the 120 125 130

other side thereof, and an independently operating valve-controlled means for opening the outgoing part of the conduit to atmospheric pressure whereby the vacuum therein is broken without reducing the vacuum in the incoming part of the conduit.

6. Priming apparatus for rotary liquid pumps comprising in combination a gas pump having a driving connection with the liquid pump, a suction conduit connecting the liquid pump with the intake of the gas pump and provided with a float chamber having a port leading to that part of the conduit which extends from the float chamber to the gas pump, a check valve opening towards the gas pump for controlling said port, and there being an air inlet port in said part of the conduit through which air may enter the same and break the vacuum therein, and a float valve for controlling said air inlet port, the float of which float valve is contained in said float chamber.

7. Priming apparatus for rotary liquid pumps comprising in combination a rotary gas pump of the type employing water for its pumping action and having a suction conduit connecting the liquid pump with the intake of the gas pump and provided with a float chamber having a port leading to that part of the conduit which extends from the float chamber to the gas pump, a check valve opening towards the gas pump for controlling said port, and a float valve for controlling a port between the last mentioned part of the conduit and the outside air.

8. Priming apparatus for rotary liquid pumps comprising in combination a liquid pump having an inlet pipe, a gas pump, a conduit forming a connection between the liquid pump and intake of the gas pump and including a chamber adapted to receive air and liquid from the inlet pipe of the liquid pump, there being a port between said chamber and that part of the conduit leading therefrom to the gas pump controlled by a valve opening outward from the chamber, and means operating independently of said valve for freely admitting outside air to the last mentioned part of the conduit whereby the vacuum therein is broken and the vacuum pump is relieved of its work.

9. Priming apparatus for rotary liquid pumps comprising in combination a liquid pump having an inlet pipe, a gas pump, a conduit forming a connection between the liquid pump and the intake of the gas pump and having a vacuum chamber adapted to receive air and liquid from the inlet pipe of the liquid pump, there being a port between said chamber and that part of the conduit leading therefrom to the gas pump controlled by a valve opening outward from the chamber, and means operating independently of said valve for establishing communication between said last mentioned part of the conduit and the

outer atmosphere, said means being controlled by the volume of the liquid contained in the vacuum chamber.

10. Priming apparatus for rotary liquid pumps comprising in combination a liquid pump having an inlet pipe, a gas pump having a driving connection associated with the liquid pump, a conduit forming a connection between the inlet pipe of the liquid pump and the intake of the gas pump and having a part adapted to receive liquid from the inlet pipe of the liquid pump, a check valve opening towards the gas pump for opening and closing the passage through said conduit, and means responsive to variations of the volume of liquid in said conduit for breaking the vacuum in that part of the conduit between the gas pump and the part of the conduit containing the liquid.

11. Priming apparatus for rotary liquid pumps comprising in combination a rotary gas pump of the type employing water for its pumping action, a conduit connecting the liquid pump with the intake of the gas pump and including a float chamber, a water supply pipe for supplying water to said gas pump, a shut-off valve therefor, and float operated actuating mechanism for said valve having a float in said float chamber.
